(Cl. D48—32)

To all whom it may concern:

Be it known that I, Jean Husson, a citizen of
the Republic of France, residing at Courbevoie
(Seine Department), 50, rue de l'Industrie, Rep-
ublic of France, have invented a new, original,
and ornamental Design for a Signal Light, of
which the following is a specification, reference
being had to the accompanying drawing forming
part thereof.

In said drawing,

Fig. 1 is a side view of a signal light, showing
my new design.

Fig. 2 is a top view of the same.

I claim

The ornamental design for a signal light, as
shown.

JEAN HUSSON.
